Fig. 3

Fig. 4

Fig. 5

Fig. 6

Fig. 7

Fig. 8

FIGURE 1 is a perspective view of a building showing my new design as seen from the front and right side;

FIGURE 2 is a front elevation view thereof;

FIGURE 3 is a left side elevation view thereof;

FIGURE 4 is a rear elevation view thereof;

FIGURE 5 is a perspective view of a second species thereof as seen from the front and left side;

FIGURE 6 is a front elevation view of the second species thereof;

FIGURE 7 is a right side elevation view of the second species thereof; and

FIGURE 8 is a rear elevation view of the second species thereof.

The dominant features of the design reside in the portions shown in full lines.

I claim:

The ornamental design for a building, substantially as shown and described.
